US0D1070823S

(12) **United States Design Patent** (10) Patent No.: **US D1,070,823 S**
He et al. (45) Date of Patent: ** Apr. 15, 2025

(54) **EARPHONE**

- (71) Applicant: **SHENZHEN BASEUS TECHNOLOGY CO., LTD**, Shenzhen (CN)
- (72) Inventors: **Jinhua He**, Guangdong (CN); **Linsong Chen**, Guangdong (CN); **Jiaqi Zhang**, Guangdong (CN)
- (**) Term: **15 Years**

(21) Appl. No.: **35/519,467**(22) Filed: **Nov. 9, 2023**(80) **Hague Agreement Data**Int. Filing Date: **Nov. 9, 2023**Int. Reg. No.: **DM/233798**Int. Reg. Date: **Nov. 9, 2023**Int. Reg. Pub. Date: **Dec. 22, 2023**(30) **Foreign Application Priority Data**

Aug. 8, 2023 (CN) 202330504119.2

(51) LOC (15) Cl. **14-01**

(52) U.S. Cl.

USPC ..... **D14/223**(58) **Field of Classification Search**

(57) **CLAIM**

The ornamental design for an earphone as shown and described.

DESCRIPTION

1. Earphone

1.1 : Front

1.2 : Back

1.3 : Left

1.4 : Right

1.5 : Top

1.6 : Bottom

1.7 : Perspective

The lines shading in the figures represents contour and not surface ornamentation.

(Continued)

The portions of the article shown in broken lines form no part of the claimed design.

1 Claim, 7 Drawing Sheets
